UNITED STATES PATENT OFFICE.

WILLIAM BREWSTER CHAPMAN, OF NEW YORK, N. Y., ASSIGNOR TO CHAPMAN ENGINEERING CO., OF NEW YORK, N. Y., A CORPORATION OF NEW YORK.

GAS-PRODUCER.

1,182,640.

Specification of Letters Patent.

Patented May 9, 1916.

Application filed February 13, 1912. Serial No. 677,339.

To all whom it may concern:

Be it known that I, WILLIAM B. CHAPMAN, a citizen of the United States, and a resident of the city of New York, borough 5 of Manhattan, county and State of New York, have invented certain new and useful Improvements in Gas-Producers, of which the following is a full, clear, and exact description.

10 The object of my invention is to insure uniformly distributing the green coal over the surface of the burning fuel in gas producers and simultaneously to rake or harrow the surface of the coal as it becomes 15 affected by the fire, thereby raking up the crust or cake which tends to form on top of the fuel bed by reason of the distillation of the hydro-carbon, preliminary to the actual burning of the coal and filling up or 20 closing the holes or gaps which constantly tend to form in the fire bed.

My present improvements are especially applicable to the ordinary type of gas producer, consisting of a stationary body or 25 shaft in which reactions are brought about by an upward draft current. Heretofore such producers have usually been supplied with a stationary top or charging floor, fitted with a charging hopper or other means 30 of introducing the fuel, and the producer often provided with mechanical devices in one form or another for agitating or shaking the fire bed.

My present invention contemplates the 35 provision for such producers of a rotatable head or top, the same provided with a hopper for the green coal, which extends downward below the top to the level of the burning fuel or fire within the producer and 40 which extends laterally from approximately the center of the producer outward to the side. This rotating top is fitted to the stationary body of the producer and in turn carries the hopper with it, sweeping the 45 open lower end of the hopper over the surface of the fire, with the double result of uniformly spreading the fresh coal and raking and breaking up the surface of the burning or gasifying fuel and closing the gaps.

50 My invention involves other features of importance, all of which will be fully set forth hereinafter and particularly pointed out in the claims.

For the purpose of a specific description 55 of the invention, reference is now had to the

accompanying drawings, which represent, as an example, the preferred embodiment of my invention.

In these drawings—Figure 1 is a plan view of a producer equipped with my invention; Fig. 2 is a vertical section on the line 2—2 of Fig. 1; and Fig. 3 is a detail section on the line 3—3 of Fig. 1 showing the coal hopper.

10 indicates the body of a producer, which as here shown is of the stationary brick-lined type with an upwardly flowing draft current and a gas outlet conduit 11 near the top. At the upper end of the producer body 10 is the usual charging floor 12, which 15 extends to the sides of the producer body as shown in Fig. 2. The fuel bed within the producer is maintained at a predetermined height, as indicated, for example, at the point *a* in Fig. 2, the same being below 20 the gas outlet 11.

The producer has a revolving top or head which is preferably metal water-cooled to prevent burning. Said head as here shown comprises an outer annular section 14 and 25 a circular central section 15, the same being suitably matched together for convenience in construction and for the further purpose of preventing destructive stresses, due to the heat to which the parts are necessarily 30 subjected. The whole is flanged as shown or otherwise formed to be water flooded through a supply pipe 16.

17 indicates an overflow pipe for withdrawing the water so that a circulation may 35 be maintained in accordance with the common practice.

The whole top is designed to rotate on the stationary producer, for which purpose the top has a peripheral gear 18, engaged by 40 push and pull pawls 19 actuated by a suitable eccentric on a slowly rotating lay shaft 20, in which manner, or by other devices as may be preferred, the aforesaid rotating motion is imparted to the top, but said motion 45 being intermittent owing to the character of the gear.

21 indicates a water seal between the top and body and 22 rollers for rotatably supporting the top.

105 The top carries, as here shown in its central section 15, a hopper 23 to receive the green coal from a chute 24 or other source of supply. This hopper 23 is eccentrically 110 located on the rotating top, though this is

not, with respect to the hopper, necessarily essential. It is essential, however, that the spreading and harrowing magazine be thus eccentrically located and that it communicate with the hopper in the manner shown best in Fig. 2. This magazine is indicated at 27 in the drawings. It consists in a metal structure communicating with the base of the hopper 23 and having its inner wall extending down in or adjacent to the axis of rotation of the top and its outer wall flaring outward into proximity to the outer side of the body of the producer. The bottom of the magazine is open, as shown, and it constitutes, therefore, the radius of the producer body. This spreading and harrowing magazine 27, together with the receiving hopper 23, moves bodily with the rotating top of the producer, and the open lower end of the magazine extends down to the upper surface of the hot or burning fuel contents of the producer, the unburned or green coal is fed into the hopper 23 and from this into the magazine 27 and in operation a mass of this green coal is maintained continually in the magazine by continual feeding from the hopper 23. Therefore, as the top and its attachments are rotated on the stationary producer body, the magazine is swept in a circular path bodily over the top of the burning fuel. By reason of the radial position of the magazine, it, in its movement, crosses the whole surface of the fire and the coal from the magazine is fed in what might be called a compensating manner, *i. e.*, the coal is put in in low spots and withheld in high spots, resulting in an even and level fire bed. Further and of even greater importance, blow holes or chimney-like apertures, which usually form in the fire bed and result in a poor gas with high CO_2 content, are prevented from forming, by the constant filling-in effect resulting from the continual harrowing. This breaks up the crust which tends to form and effectually closes said blow holes, thus keeping the surface of the fire open and firm and insuring uniform and thorough reaction in accordance with the known operation of gas producers. The magazine for the unburned or fresh coal must project below the gas outlet flue 11 because the level *a* of the coal cannot rise above the flue. This requires a relatively long fuel magazine and in connection with such a magazine the intermittent motion of the top and its attachments is important, because the unburned coal when acted on by the heat tends to agglomerate and clog in the magazine and is only dislodged by the jarring or vibration of the magazine due to the intermittent movement of the top.

The top and its attachment are designed by preference to rotate in the direction indicated by the arrows in the drawings and,

for this purpose, the rear or following wall 27^a of the magazine, is projected down and slightly below the leading and side walls of the magazine. Said following wall 27^a, therefore, is the actual element on the raking of the fire surface as well as in the spreading and distribution of the green coal over the same. For obvious reasons I prefer to water-cool this following wall 27^a, and this is best effected by a downtake pipe 75 28 leading into the cavity of said wall and fed from the flood of water on the producer top, an outtake pipe 29 discharging back into said flood.

With most coals used in gas producers, 80 the fire bed, if not properly agitated, will become extremely porous or honeycombed, the best part of the coal burning away and leaving the skeleton of the fuel hanging up or arching across from wall to wall and 85 not moving downward in a compact mass as it should. When this condition arises in ordinary producers, the gas becomes very poor in quality and the fire bed has to be tamped. To overcome this tendency of the 90 fire bed to "hang up" and become honeycombed, the bottom edge of the above-mentioned water-cooled spreader wall is made slightly beveled, so as to produce a down-stroking effect as it passes over the 95 fire bed, and as this "hanging up" is most pronounced near the walls of the producer, the beveling or down stroke at this point is increased proportionately.

Many modifications may be made in the 100 construction of my improved producer without departing from the spirit of the invention, the real merit of which lies in the charging of coal in front of a constantly revolving spreader wall. Thus, the hopper 105 27, as such might be dispensed with, except that it has this advantageous effect, to wit: it prevents a puff of smoke from going out of the gas outlet nozzle every time a new charge of coal is dropped from the hopper. 110 This is true, for when the chamber is used, the fine coal and dirt as it comes from the hopper, must first pass down through the fresh coal in the chamber and out under the bottom edge of the chamber before it 115 can escape to the gas outlet nozzle; and this retarding effect has considerable influence in producing a gas freer from smoke and other impurities than it would otherwise be. Further, the hopper or, if it be omitted, the 120 spreader wall need not necessarily extend to the rotating top, as a space might be left between its upper edge and said top. With this construction it would still perform its principal function, which is to act as a 125 sweep passing over the fire bed.

Having thus described my invention, what I claim as new and desire to secure by Letters Patent is:

1. A gas producer with a stationary body 130

- extending up to the top thereof, a head 5
rotating on said body and a coal magazine
eccentrically carried on said head and pro-
jecting downward with its lower end open
at the level of the fuel bed within the pro-
ducer, the following wall of said magazine 25
projecting slightly below the leading wall.
2. A gas producer with a stationary body
extending up to the top thereof, a head
10 rotating on said body and a coal magazine
eccentrically carried on said head and pro-
jecting downward with its lower end open
at the level of the fuel bed within the pro-
ducer, the following wall of said magazine
15 projecting slightly below the leading wall
and being chambered, and means for circu-
lating a cooling medium through said cham-
ber.
3. A gas producer with a stationary body
20 extending up to the top thereof, a head ro-
tating on said body and a coal magazine
eccentrically carried on said head and pro-
jecting downward with its lower end open
at the level of the fuel bed within the pro-
ducer, the following wall of said magazine
25 projecting slightly below the leading wall,
said following wall having a beveled edge
in contact with said fuel bed.
4. A gas producer with a stationary body
extending up to the top thereof, a head ro-
tating on said body and a coal magazine
30 eccentrically carried on said head and pro-
jecting downward with its lower end open at
the level of the fuel bed within the producer,
the following wall of said magazine pro-
jecting slightly below the leading wall, said
35 following wall having a beveled edge in
contact with said fuel bed, said beveled edge
rising from the fuel bed at the end adja-
cent the walls forming said producer body. 40

In testimony whereof I have signed my
name to this specification in the presence of
two subscribing witnesses.

WILLIAM BREWSTER CHAPMAN.
